FIG. 5.

George Willard Beijerinck Inventor

UNITED STATES PATENT OFFICE.

GEORGE HILLARD BENJAMIN, OF NEW YORK, N. Y.

CONTINUOUS TUNNEL-KILN.

1,295,955.

Specification of Letters Patent.

Patented Mar. 4, 1919.

Application filed February 1, 1917, Serial No. 145,959. Renewed July 16, 1918. Serial No. 245,218.

To all whom it may concern:

Be it known that I, GEORGE HILLARD BENJAMIN, a citizen of the United States, residing at New York, in the county and State of New York, have invented certain new and useful Improvements in Continuous Tunnel-Kilns, of which the following is a specification.

My invention relates to certain improvements in continuous tunnel kilns of the muffle type, such as are especially adapted for use in the manufacture of tiles, pottery, and the like.

In a prior application, Serial No. 99,540 filed May 24, 1916, I have described a construction in which the heating means employed consists of a series of separate chambers arranged longitudinally in line, on each side of the main chamber, and each of such chambers adapted to be fed with gas and air under pressure, proportioned to produce complete combustion at the burner orifices, the products of combustion being drawn from each chamber and utilized to heat the air used in combustion with the gas in the heating chambers, or introduced into the main chamber. In such application I have further described a means whereby heated air introduced into the main chamber in which the goods under treatment are passed, is positively circulated through such goods.

My present invention consists in a modification of the construction described in such prior application, so far as relates to the construction and placing of the heating chambers, as also the arrangement of the passages, by reason of which the air circulated over and around the goods carried through the main chamber, is more perfectly heated; also to other modifications, which will be pointed out in the specification.

I wish it understood that my improved continuous kiln is not only adapted for use in the manufacture of tiles, pottery and the like, but also in the manufacture of brick and for annealing and other treatment of metals, etc.

The accompanying drawings will serve to illustrate my invention, in which Figure 1 is a longitudinal section, Fig. 2 is a vertical section on the line II--II of Fig. 1, Fig. 3 is a vertical cross section on the line III--III of Fig. 1, Fig. 4 is a section corresponding to Fig. 3 and showing a modifica-

tion. Fig. 5 is a section corresponding to Fig. 3 and showing a further modification.

Referring to the drawings, 5 indicates the main chamber, which may be of any suitable construction. As the kiln is a long 60 piece of apparatus, only sufficient length is illustrated in Figs. 1 and 2 to show its general construction. Situated within the kiln, on each side, and arranged longitudinally in line, are individual heating chambers 6, 6^a, 6^b, 6^c, etc. These heating chambers may be formed of baked clay or built up of brick, and are located at a distance from the side walls and top of the main chamber, so as to form air passages 7 between the chambers 70 and the walls. The chambers 6 are so designed that their side walls 8, and the inner walls 9 of the main chamber, will occupy parallel vertical planes. The top wall 10 of the heating chambers 6, is inclined and located in a plane parallel to the plane of the roof 11 of the main chamber. The portion of the air passage 7, between the top wall 10 of the heating chambers 6 and the roof 11 of the main chamber, is inclined in an upward 75 direction. The object of this construction is to throw the incoming air against the roof 11 of the main chamber, from which it is deflected in a downward direction through the goods 12, under treatment in the main 80 chamber. The interior 13 of the chambers 6, is given such size as to permit free combustion of the gas and air introduced into the bottom of the chambers through the burners 14. The burners 14 are connected 85 through the mixing pipe 15 to a gas supply pipe 16 and an air supply pipe 17. The gas transmitted from pipe 16 is under pressure from pump 18, and the air from pump 19. The general arrangement of the gas and air 90 pumps and burners is fully described in my prior application, to which reference has hereinbefore been made, and also in my prior Patent No. 948,538 dated Feb. 8, 1910.

The purpose of giving to the heating 100 chambers the interior size, and placing them as described, is two-fold: First, to permit instantaneous combustion of the gas and air introduced into the chambers at the burner orifices and therefore, the immediate development of all of the heat units carried by the combustible mixture, with the result that perfect combustion is obtained with very much higher temperatures than is otherwise possible using gas and air; and 110

second, to utilize the heat radiated from the two sides and top of the heating chambers for heating the air which is circulated over the goods under treatment in the kiln, thereby using the radiated heat units to the best advantage.

In view of the fact that kilns such as described in this specification, may be employed for treating goods containing more or less water, and the further fact that when water in the form of steam is mingled with heated air, the specific gravity of the mixture is less than of air alone, it is necessary, in order to cause the air or mixture to circulate through the goods under treatment in the kiln, to provide means for creating a positive circulation of said air or mixture, and this is accomplished by means of a pump 20, which is connected to the interior of the kiln at its induction orifice, through an air passage 21, and at its eduction orifice through an air pipe 22, which is in communication with the passage 7 between each heating chamber and the inner walls of the kiln (see Fig. 4). It is sometimes desirable to allow fresh air to enter the passage 7, and to permit this I provide the valves 23 in pipe 22. I also provide a valve 24 in the pipe 25 from the eduction orifice of the pump 20, which when opened, and the valves 23 closed, allow the air to be drawn out of the kiln.

It is also sometimes desirable to add to the heat of the air introduced into the passage 7, or in other words, impart heat units in excess of those added by radiation from the chambers 6. To accomplish this, the air pipe 22 is carried through a flue 26, which conveys the products of combustion from the chambers 6 to the chimney stack 27 (see Fig. 5). In this figure, the air enters the pipe 22 through an opening 28 in pipe 22. If desired, the pipe 22 may be connected to the eduction orifice of the pump 20, in which case circulation of the air will be effected, as in the manner shown in Fig. 4, and further, heat units added to the air by the heat units passing through the flue 26.

The goods 12 under treatment, are mounted on a truck 29, which moves over rails 30 situated beneath the main chamber. In order to compel the hot air to pass through the goods on the truck 29, rather than flow along the outer walls of the chambers 6, the top of the truck is provided with a plate 31, the sides 32 of which are turned downward at a right angle, and when the truck is progressed, move in boxes 33 which are filled with sand, thus forming a sand seal. An opening 34 is provided in the plate 31.

I wish it understood that the drawings in this application are in a sense diagrammatic, and merely intended to illustrate such a construction as may be used, and that very many modifications may be made, not only

in the general construction, but in the size and relation of pipes and passages, position of the valves, etc., without in any wise departing from the intent of my invention.

The general operation of my improved kiln will be readily understood. Assuming the goods to be treated in the kiln, to contain some moisture, and that it is desirable to evaporate such moisture before subjecting the goods to the temperature necessary to vitrify the material, the gas and air introduced into the chambers 6 is regulated so that the temperature in this chamber will be comparatively low; more gas and air will be introduced into chamber 6^a, more into 6^b and still more into chamber 6^c, it being assumed that the maximum temperature of the kiln is at 6^c. For the purpose of description it is assumed that the drawing (Fig. 1) shows one half of the length of the kiln. It may be further assumed that vitrification is effected in the zone in which the chambers 6^a are located. Consequently all that is necessary to temper the goods is to decrease the heat from such zone 6^a to the outlet of the kiln, in which case it is not necessary to introduce any gas into the chambers beyond 6^c. Sometimes, however, it is necessary to hold the vitrifying temperature for a time, in which case the gas may be introduced into one or more of the chambers beyond 6^c in any proportion required to give the necessary heat.

It will be understood that by reason of the arrangement of the chambers disclosed, and the fact that each chamber is independent of the other chambers, both structurally and so far as its supply of gas and air is concerned, the temperature at any portion of the length of the kiln can be regulated to suit the requirements of the goods under treatment. It will be further observed that the construction is such that the air carrying the heat units and acting on the goods under treatment, can be regulated to suit requirements. For instance, assuming the goods under treatment to contain more or less moisture when introduced into the kiln, it is an advantage not to cause the air to pass over the goods more than once, in which case the air will be fed through the pipe 22 and drawn out through the pump 20 to be discharged into the atmosphere, thus getting rid of the moist air. By reason of the construction disclosed, the air fed to the furnace over the heating chambers 6, may be drawn out to be discharged into the atmosphere, whereas the air fed to the furnace over the heating chambers 6^a, 6^b and 6^c may be continuously circulated, thus converting the heat units and progressively adding to them, and further, cold or heated air may be fed into the kiln at that portion of the kiln beyond the chamber 6^c.

The requirements of temperature in a tun-

nel kiln in which the goods treated are moved continuously or by step-by-step motion through the kiln, are so various, owing to the difference in size, character or material of which the goods are made, that no general statement can be made regarding the temperatures to be produced at any point or points along the length of the kiln. Such temperatures, however, can readily be determined by experiment, and one particular advantage of the kiln described in this specification is that by regulating the temperature of gas and air introduced into the heating chambers, alone or in connection with the air introduced into the main chamber, heated or cold, a greater number of technical results can be obtained than is possible in any other furnace construction of which I am aware.

I have shown in the drawings, but one pump for controlling the circulation of the air. Where the air is to be controlled in differing manner over different sections, the number of pumps employed will be in accordance with the variations in the air circulation. Practically, however, the valves and other devices may be used in connection with a single pump. Such arrangement is so well known, that is has not been considered necessary to illustrate the employment of more than one pump.

Having thus described my invention and the manner in which it is to be used, I claim:

1. A tunnel oven of the type described, comprising a main chamber, a plurality of structurally independent heating chambers arranged longitudinally in line on each side of the main chamber, each heating chamber having a vertical height corresponding to the maximum horizontal plane occupied by the goods under treatment in passing through the chamber, and such chamber located at such a distance from the side walls and top of the main chamber as to provide an air passage between the respective chambers, and said heating chambers having such an interior capacity as to permit free combustion of the gaseous fuel introduced into the bottom of the chamber, together with means for introducing gas and air under pressure into said heating chambers.
2. A tunnel oven of the type described, comprising a main chamber, a plurality of structurally independent heating chambers arranged longitudinally in line on each side of the main chamber, each heating chamber having a vertical height corresponding to the maximum horizontal plane occupied by the goods under treatment in passing through the chamber, and such chamber located at such a distance from the side walls and top of the main chamber as to provide an air passage between the respective chambers, the said heating chambers having such an interior capacity as to permit free combustion of the gaseous fuel introduced into the bottom of the chamber, together with means for introducing gas and air under pressure into said heating chambers. 70
3. A tunnel oven of the type described, comprising a main chamber, a plurality of structurally independent heating chambers arranged longitudinally in line on each side of the main chamber, each heating chamber located at a distance from the top and side walls of the main chamber, said chamber consisting of two parallel vertical walls and an inclined top wall and having a vertical height corresponding to the maximum horizontal plane occupied by the goods under treatment in passing through the chamber, and such chamber having such an interior capacity as to permit free combustion of the gaseous fuel introduced into the bottom of the chamber, together with means for introducing gas and air under pressure into said heating chamber. 75
4. A tunnel oven of the type described, comprising a main chamber, a plurality of structurally independent heating chambers arranged longitudinally in line on each side of the main chamber, each heating chamber having a vertical height corresponding to the maximum horizontal plane occupied by the goods under treatment in passing through the chamber, and such chamber located at a distance from the side walls and top of the main chamber, said heating chamber having such an interior capacity as to permit free combustion of the gaseous fuel introduced into the bottom of the chamber, means for introducing air into the main chamber between the sides of the main chamber and the inner sides of the heating chambers, and means for causing the air introduced to flow over the heating chambers and in a downward direction through the goods under treatment in the main chamber and out of the main chamber. 80
5. A tunnel oven of the type described, comprising a main chamber, a plurality of structurally independent heating chambers arranged longitudinally in line on each side of the main chamber, each heating chamber having a vertical height corresponding to the maximum horizontal plane occupied by the goods under treatment in passing through the chamber, and such chamber located at a distance from the side walls and top of the main chamber, said heating chamber having such an interior capacity as to permit free combustion of the gaseous fuel introduced into the bottom of the chamber, means for introducing heated air into the main chamber between the sides of the main chamber and the inner sides of the heating chambers, and means for causing the air introduced to flow over the heating chambers and in a downward direction through the goods under treatment in the main chamber and out of the main chamber. 85

treatment in the main chamber and out of the main chamber.

6. In a tunnel oven of the type described, the combination of a main chamber, a series of independent heating chambers arranged longitudinally in line on each side of the main chamber, each of said heating chambers situated at a distance from the side walls and top of said main chamber so that an air 10 passage shall exist between the two; said heating chambers having a vertical height corresponding to the maximum horizontal plane occupied by the goods under treatment in passing through the main chamber; 15 means for introducing gaseous fuel separately into each of said heating chambers; means for controlling the temperature of each of said heating chambers, together with means for creating an air circulation in an 20 upward direction over said heating chambers and then in a downward direction over said heating chambers and through the goods under treatment in the main chamber.

7. A tunnel oven of the type described, 25 comprising a main chamber, a series of independent heating chambers arranged longitudinally in line on each side of the main chamber, each of said heating chambers situated at a distance from the side walls 30 and top of said main chamber so that an air passage shall exist between the two; said heating chambers having a vertical height corresponding to the maximum horizontal plane occupied by the goods under 35 treatment in passing through the main

chamber, means for introducing gaseous fuel separately into each of said heating chambers, means for controlling the temperature of each of said heating chambers, together with means for introducing air in an upward direction in the space between the back of the heating chamber and the side walls of the main chamber, and then causing the air after passing the heating chambers to pass in a downward direction through the 40 goods under treatment in the main chamber. 45

8. In a tunnel oven of the type described, the combination of a main chamber, a series of independent heating chambers arranged longitudinally in line on each side 50 of the main chamber, each of said heating chambers having their tops substantially in the same horizontal plane as that occupied by the goods under treatment in passing through the chamber, an air passage between said chambers and the walls of the top of the main chamber, means for heating said heating chambers, together with means for creating an air circulation in an upward direction through such passage over 55 the rear of said heating chambers and then in a downward direction over said heating chambers and through the goods under treatment in the main chamber.

In testimony whereof I affix my signature, in the presence of two witnesses.

GEOERGE HILLARD BENJAMIN.
